KEY-SEAT REAMER**Lorenzer D. V. Wisenbaker, Houston, Tex.****Application March 12, 1957, Serial No. 645,606****2 Claims. (Cl. 255—73)**

This invention relates to a key-seat reamer and more particularly to a reamer which is adapted to be connected into a string of drill pipe for use in well drilling operations and by the use of which a key-seat formed in a well bore may be enlarged to prevent sticking the drill pipe in such a seat.

In the drilling of wells, such as oil and gas wells, key-seats or slots are often formed in the well bore due to rotation of the drill pipe in contact with the wall of the bore at a curved portion of the bore. The drill pipe is of somewhat smaller external diameter than the external diameter of the drill bit, so that the rotation of the drill pipe in contact with the wall of the bore at a curved portion of the bore results in the formation of a longitudinal slot or key-seat which is of smaller diameter than that of the bore, and in withdrawing the drill pipe from a well bore in which such a key-seat is present there is danger that the drill collars may enter and become wedged in the key-seat.

The present invention has for an important object the provision of a reamer which is adapted to be connected into a string of drill pipe and which is rotatable with the string to ream away the formation and enlarge the well bore at a key seat.

Another object of the invention is to provide a key-seat reamer adapted to be connected into a drill string and which is shaped to permit circulation of drilling fluid in the bore past the reamers during the drilling operation.

A further object of the invention is the provision of a key-seat reamer embodying a tubular body and having external, spiraled cutting elements extending longitudinally of the body in circumferentially spaced relation.

Another object of the invention is to provide a key-seat reamer of the kind referred to which is shaped to be easily disengaged from a key-seat in a well bore by longitudinal movement of the drill string in the event that the reamer should become wedged in such a key-seat.

A further object of the invention is the provision of a key-seat reamer having a tubular body of substantially uniform external diameter throughout its length and provided with elongated external, circumferentially spaced cutter elements formed with cutting edges which taper from a point mediate the ends of the elements toward their opposite ends.

Another object of the invention is to provide a key-seat reamer having a tubular body of substantially uniform diameter throughout its length and provided with elongated, longitudinally tapering, spiraled, external cutter elements formed with leading edge portions which extend radially beyond the weld deposit and with trailing surface portions which are joined to the external surface of the body by deposited weld material.

The above and other important objects and advantages of the invention may best be understood from the following detailed description constituting a specification of the same when considered in conjunction with the annexed drawings, wherein—

Figure 1 is a side elevational view of the invention,

2

on a reduced scale, showing the invention connected into a drill pipe in a well bore and illustrating the manner in which the invention is used;

Figure 2 is a side elevational view of the invention, showing the same detached from the drill string and illustrating details of construction of the reamer;

Figure 3 is a bottom plan view of the invention as seen in Figure 2; and

Figure 4 is a cross-sectional view, on a somewhat enlarged scale, taken along the line 4—4 of Figure 2, looking in the direction indicated by the arrows.

Referring now to the drawings in greater detail, the reamer of the invention is illustrated in Figure 1, connected into a drilling string of conventional construction, designated S, positioned in the bore W of a well, such as an oil well, having a key-seat K therein, such as might be formed by rotation of the drill string in contact with the wall of the bore at a curved portion of the bore.

20 In well equipment of this type the drill pipe is of substantially smaller external diameter than the bore W of the well, while the drilling bit, not shown, attached to the lower end of the string has an external diameter which is the same as that of the bore. Above the drilling bit, one or more drill collars, also not shown, are connected into the string whose external diameter is usually somewhat smaller than that of the bit but substantially larger than the external diameter of the drill pipe. In the presence of a key-seat in the well bore, such seat has a diameter equal to the external diameter of the drill pipe but smaller than that of the drill collars which have a tendency to enter the seat during withdrawal of the string from the bore and to become wedged therein.

It is for the purpose of overcoming the above difficulty 35 encountered in the presence of key-seat formations in well bores that the present invention is provided, the key-seat reamer comprising a tubular body 10, of substantially uniform external diameter throughout its length, having an externally threaded pin 12 at one end and an internally threaded box 14 at the other end by which the body may be connected into the drill pipe S. The body 10 has an external diameter substantially equal to that of the drill pipe, and is provided with external, elongated, spiraled cutter elements 16 welded to the external surface of the body in circumferentially spaced relation.

Each of the cutter elements 16 is preferably of rectangular shape in cross-section, having one face positioned in tangential relation to the external surface of the body and secured thereto by means of weld deposits, indicated at 18 and 20 along the longitudinally extending sides of the elements, and which deposits may extend somewhat inwardly beneath the elements to securely bond the elements to the body.

55 The elements may conveniently be applied to the body by welding one end of each element to the body and fitting the element in a spiral to the body by hammering or clamping the element in the desired spiraled position and welding the same along its opposite sides to the body, to form externally opening, spiraled, grooves or channels 22, spaced circumferentially about the body and open at their opposite ends.

When the cutter elements have been so applied to the body, the body is preferably supported in a lathe for rotation about its longitudinal axis and the other faces of the elements are cut or ground down to form curved outer surfaces 24 which taper from a location of maximum diameter mediate the ends of the elements toward locations of minimum diameter at the opposite ends of the elements, as best seen in Figure 2.

60 The leading or cutting edge portions of the cutter elements project radially beyond the weld deposits 18 and are provided with built up deposits 26 of hardened cut-

ting material or otherwise treated to form hardened cutting edges.

The weld deposits 20, along the trailing faces of the cutter elements, preferably extend entirely across the trailing faces, as best seen in Figure 4, to securely bond the elements to the body and to form a substantial backing and reinforcing for the elements to strengthen the same.

After the cutter elements have been welded in place on the body and cut or ground to shape and the hard material 26 deposited on the leading edge portions the deposited material is ground down to shape the cutting edges to conform to the longitudinal taper of the elements. The maximum external diameter of the reamer is preferably somewhat smaller than the diameter of the bore W but is substantially greater than the external diameter of the drill pipe.

In making use of the invention, constructed as described above, the reamer is connected into a string of drill pipe in the manner shown in Figure 1, so that the reamer will rotate with the string. During normal drilling operations the reamer will merely rotate with the string and circulation of drilling fluid in the well bore may take place freely through the grooves 22 between the cutting elements 16. When it is desired to remove the string, however, should the reamer enter a key-seat in the bore in which there would be likelihood that the drill collars might become stuck, the end portions of the cutter elements 16, where cutting portion of the reamer is of smallest diameter will enter the key-seat first and the reamer may be rotated with the string to cut away and enlarge the key-seat. In the event that the reamer should become wedged in the key-seat, the reamer, because of the tapering configuration of the cutter elements may be readily released by the exertion of a downward force on the string. Moreover, because of the tapering shape of the cutter elements due to the presence of the weld deposits 18 and 20, mud or other similar material does not clog the grooves and interfere with free circulation of fluid past the reamer.

During the reaming operation of the tool there is a tendency, due to the spiraled arrangement of the cutter elements, for the reamer to move out of the key-seat, so that the reamer is prevented from becoming stuck in the key-seat as the reamer is moved into the key-seat while being rotated.

Because of tapering shape of the reamer and the arrangement of its cutter elements the reamer of the invention may also be used by inserting the same in a well casing to cut away portions of the casing where the same may be bent, collapsed, or otherwise obstructed, and is capable of use under many different conditions to facilitate the drilling and production of wells.

The invention thus provides a key-seat reamer which

is of simple design and rugged construction and which may be economically manufactured.

It will be understood that the embodiment of the invention disclosed herein is intended by way of illustration only and that various changes can be made in the same within the spirit of the invention and the scope of the appended claims.

Having thus clearly shown and described the invention, what is claimed as new and desired to secure by

10 Letters Patent is—

1. A key-seat reamer comprising a tubular body, means for connecting the body at its opposite ends into a string of drill pipe for rotation with the string in a well bore, external, peripherally spaced, radially extending cutter elements on the body, each of said elements having a flat surface positioned in tangential contact with the external surface of the body and an advancing side face forming a leading edge and a trailing side face, weld deposits along said faces securing the elements to the body, the weld deposit along said advancing faces terminating radially inwardly of said leading edges and the weld deposits along said trailing faces extending radially substantially completely across the width of said trailing faces.
2. A key-seat reamer comprising a tubular body having a substantially uniform external diameter throughout its length, means for connecting the body at its opposite ends into a string of drill pipe for rotation with the string in a well bore, external, peripherally spaced, radially extending cutter elements on the body, each of said elements having a flat surface positioned in tangential contact with the external surface of the body and an advancing side face forming a leading edge which slopes longitudinally from a location of maximum external diameter mediate the ends of the body to a location of minimum external diameter adjacent an end of the body, radially outwardly tapering weld deposits along the faces securing the elements to the body, the weld deposits along said advancing faces terminating radially inwardly of said leading edges and the weld deposits along said trailing faces extending radially substantially completely across the width of said trailing faces.
